UNITED STATES PATENT OFFICE

GEORGE WEBB, OF WEST HARTFORD, CONNECTICUT, ASSIGNOR TO COLT'S PATENT FIRE ARMS MANUFACTURING CO., OF HARTFORD, CONNECTICUT, A CORPORATION OF CONNECTICUT

WASHING MACHINE

Application filed May 5, 1928. Serial No. 275,502.

The invention relates particularly to a washing machine adapted for washing articles such as newly machined parts having chips still adhering to them. However, machines embodying the invention are by no means limited in their utility to the washing of such newly machined parts and may be used for washing articles of any suitable kind.

A machine of the type to which the invention relates comprises a substantially horizontal conveyor for moving through the machine the articles to be washed, a tank at one side of the conveyor and below the level of the article moving part thereof for containing a supply of cleansing fluid, means for withdrawing liquid from the tank and delivering it against articles being moved by the conveyor and a shield under the path of the articles through the machine for receiving the liquid so delivered and returning it to the tank. The conveyor is ordinarily of the openwork type, with the result that small articles that are being washed, or other small bodies, may pass through the meshes of the upper run of the conveyor. It is one of the objects of the present invention to provide means for holding such small articles or other bodies to prevent them from passing either onto the lower run of the conveyor or into the tank.

The accompanying drawings are intended for illustrative purposes only and are not to be construed as defining or limiting the scope of the invention, the claims forming a part of this specification being relied upon for that purpose.

Of the drawings:

Fig. 1 is a side view, a part of the tank being broken away to show interior parts.

Fig. 2 is a horizontal sectional view taken approximately along the broken lines 2—2 of Figs. 1 and 3.

Fig. 3 is a right end view of the machine, the conveyor belt being omitted for the sake of simplicity.

Fig. 4 is a fragmentary side view similar to Fig. 1 but showing an alternate construction embodying the invention.

Fig. 5 is a fragmentary vertical sectional view taken along the line 5—5 of Fig. 4.

Referring to the drawings, 1 represents the main casing of the machine, this casing being generally rectangular in transverse cross section as shown in Fig. 3 and being provided with side walls 2 and 3, with a top wall 4 and a bottom wall 5. The ends of the casing are open at least in part, as shown at 6 and 7, to permit the articles to be washed to be introduced at one end and to permit the washed articles to be removed at the other end.

The casing 1 is supported in a relatively elevated position by means of a suitable framework, this framework being preferably constructed of structural steel parts. The framework includes four vertical members 8, 8 and 9, 9 located at the respective corners of the casing and extending downward to form main supporting legs for the machine. The framework may include such other structural steel members as may be necessary, such as longitudinal connecting members 10, 10 and transverse members 11. There are also provided transverse members 12 provided with legs 13.

Means is provided for moving the articles to be washed through the casing 1 from end to end thereof, and so far as the present invention is concerned this moving means can be varied within wide limits. As shown, however, the means for moving the articles comprises an endless open-work conveyor which

extends through the casing substantially from end to end thereof and which is adapted to have the articles placed directly upon it. The endless belt of the conveyor is represented in the drawings at 14, this belt being supported at the ends of the machine by means of drums 15 and 16. The belt may be provided with rollers 17, 17 adapted to engage a track 17^a. The conveyor is operated preferably in the direction of the arrow shown in Fig. 1, the articles being placed upon the belt at the left hand end of the machine and being discharged therefrom at the right hand end of the machine.

A tank 18 is provided for containing a supply of cleansing liquid, this tank being located at one side of the casing 1 and at one side of the path of the articles through the said casing and below the level of the said path. As shown the said tank 18 is directly

connected with the main casing 1 and is supported in part on the members 12, 12 of the framework. The tank is provided with an openable cover 18^a, preferably hinged at 18^b.

5 Provision is made for withdrawing the cleansing liquid from the tank 18 and for delivering it against the articles being moved through the casing by the conveyor 14. As illustrated spray pipes 19, 19 extend transversely of the casing above the path of the articles therethrough and other spray pipes 20, 20 extend transversely of the casing below the said path of the articles. The pipes 19, 19 are provided with downward directed 10 spray orifices and the pipes 20, 20 are provided with upward directed spray orifices. As illustrated there are three spray pipes above the path of the articles and three spray pipes below the said path but the exact number is 15 not essential. The cleansing liquid is supplied to the spray pipes 19, 19 and 20, 20 by means of supply pipes 21 and 22, these pipes preferably being located on the exterior of the casing and at the sides thereof opposite 20 the tank. For forcibly delivering the cleansing liquid to the spray pipes through the said supply pipes 21 and 22 there is provided a pump device 23. The details of the pump device may be widely varied but I have illus- 25 trated a device having a single main casing 24 with three separate pump compartments therein, the said pipes 21 being connected respectively with the said compartments. Three separate impellers 25, 25 are mounted 30 in the said compartments on a common drive shaft 26. Inlet pipes 27, 27 lead from the tank 18 and communicate with the three compartments of the pump device. A suitable means is provided for rotating the shaft 26 and thus operating the pump, and an electric motor 28 is illustrated for that purpose. It will be observed that the pump device 23 and the motor 28 are located in the space vertically below the casing 1 and are arranged 40 with their axes extending longitudinally.

In order that the liquid delivered through the spray pipes 19, 19 and 20, 20 may be returned to the tank 18 I provide the casing 1 with a discharge opening 29 at one side thereof of the said opening being so positioned as to communicate with the upper portion of the tank 18. In order to facilitate the flow of liquid to the discharge opening 29 the bottom wall 5 of the casing 1 may be suitably 50 inclined as shown. Projecting from the casing at the discharge opening 29 there may be provided a short discharge spout or duct 30.

For operating the conveyor 14 any suitable mechanism may be provided but I prefer and 60 have shown a mechanism operated by the same motor 28 which drives the pump 23. As illustrated there is a gear box 31 having a main shaft 32 which is directly connected with the shaft 26 of the pump. Mounted on 65 the shaft 32 is a worm 33 which meshes with

a worm wheel 34 on a short transverse shaft 35. The shaft 35 serves to rotate a sprocket wheel 36, connection being made through a clutch 37.

The sprocket wheel 36 is engaged by a 70 chain 38 which extends over a sprocket wheel 39 connected with the drum 16. Through the parts described power is transmitted from the shaft 26 to the conveyor to operate it in the direction indicated. 75

The tank 18 may be considered as comprising two distinct portions which are separated from each other by a vertical or approximately vertical plane, this plane preferably being arranged transversely of the direction 80 of the conveyor movement. The inlet pipes 27, 27 are so positioned and connected as to receive liquid from one portion of the tank, and the discharge opening 29 is so positioned as to return the liquid into the other portion 85 of the tank. As shown the receiving portion of the tank is at the left hand end thereof and the discharge portion is at the right hand end thereof.

Between the two said portions of the tank 90 I provide a suitable baffle means which permits the flow of liquid from the receiving portion to the discharge portion, but which nevertheless serves to cause the major portion of any solid matter in the liquid to be deposited in the said receiving portion. I have shown two different baffle constructions. As illustrated in Fig. 1 there is provided a baffle plate 40 which extends entirely across the tank but which terminates above the bottom 100 of the tank so as to leave a passageway. Associated with the baffle plate 40 is a second baffle plate 41 which extends transversely of the tank and upward from the bottom thereof. The baffle plate 41 may terminate at a 105 short distance above the bottom of the tank, but I have shown it as extending above the liquid level and as being provided with a large opening therein. A screen 42 is provided in register with the opening in the baffle 110 plate 41. Preferably the screen 42 is removable being held in place by suitable guide bars 43, 43 and 44 secured to the plate 41. With the cover 18^a open the screen 42 can be slid upward out of the tank for inspection 115 or cleaning. Preferably the two baffle plates 40 and 41 are inclined as shown but this is not essential.

From the description which has been given it will be obvious that a continuous circulation of liquid is maintained by means of the pump 23, the liquid being withdrawn as stated 120 from the right hand discharge portion of the tank 18 and being forcibly delivered onto the articles to be washed through the spray pipes 19, 19 and 20, 20. From the said articles the fluid falls onto the bottom wall 5 of the casing and thence flows through the opening 29 into the receiving portion of the tank 18. Inasmuch as the liquid is withdrawn from 125 130

the right hand discharge portion and is delivered to the left hand receiving portion it is obvious that a compensating flow must take place from the said receiving portion to the 5 said discharge portion. Such flow is permitted by the baffle means which has been described, but it is to some extent retarded thus maintaining the liquid in the receiving portion in a sufficiently quiescent state to permit 10 any solid particles in the fluid to settle by gravity to the bottom of the tank. Obviously the liquid must pass under the baffle plate 40 and over the portion of the baffle plate 41. When a screen such as 42 is provided 15 the liquid must pass through the screen. The screen will serve to catch any particles which may have failed to settle to the bottom of the receiving portion of the tank. If the screen becomes clogged or partly clogged it 20 can be easily removed for cleaning as already described. If desired the baffle plates 40 and 41 and the screen 42 may be supplemented by means of screening devices 45, 45 at the entrance ends of the pipes 27, 27.

25 Liquid may be introduced into the tank 18 by means of a supply pipe 46. Excess liquid may flow through an opening in the end of the tank into a basin 47 and thence through a pipe 48 to the main discharge pipe 49. The 30 tank may be drained into the said pipe 49 through openings in the bottom, which are normally closed by the stand pipes 50 and 51. These stand pipes normally serve as auxiliary overflow means and they can be 35 lifted when necessary to permit the draining of the tank.

When an openwork conveyor such as 14 is used there is some possibility that small articles being washed, or other solid bodies 40 such as large chips, may fall through the upper strand or run of the conveyor and onto the lower strand or run thereof. Such articles although falling through the upper strand of the conveyor might fail to fall 45 through the lower strand with the result that they would be carried toward the left and jammed between the lower strand of the conveyor and the drum 15. To avoid this possibility it may be desirable for certain classes 50 of work to provide an auxiliary guard or shield including a grating or screen to catch and retain such articles. As illustrated I have provided two inclined guide plates 52, 52 which extend entirely across the casing 1 55 between the strands of the conveyor. Located between these two guide plates are screens or gratings 53, 53. The screens or gratings 53, 53 have a relatively coarse mesh, the mesh being selected to enable them to 60 catch any articles which might possibly fall through the conveyor but nevertheless being coarse enough to permit any ordinary chips or other similar particles to escape. Two such screens or gratings are illustrated but 65 the number is not essential. The screens or

gratings 53, 53 are preferably removable and when two such screens or gratings are provided they may be supported in part by means of ledges formed on the plates 52, 52 and in part by means of a central cross rail 70 54. When the screens or gratings 53, 53 are to be removed access may be had to them through a door 55 formed in the side wall 2 of the casing. The door 55 as illustrated may be moved vertically upward to be opened. 75

In Figs. 4 and 5 I have shown an alternate construction in which no screen is provided at the baffle plates, but in which a suitable screen is provided elsewhere. There is provided a vertical baffle plate 56 extending 80 across the tank, the bottom of the plate being above the bottom of the tank, and there is provided a second baffle plate 57 which projects upward from the bottom of the tank. Obviously any liquid in flowing from the receiving portion of the tank to the discharge portion thereof must flow under the baffle plate 56 and over the baffle plate 57 as indicated by the arrow. This action retards the 85 flow of liquid and enables the solid particles 90 therein to settle to the bottom of the receiving portion.

Preferably a wall 58 is provided which extends longitudinally between the baffle plate 56 and the right hand end of the tank, this wall forming a compartment 59 with which the pipe inlet pipes 27, 27 communicate. The wall 58 is provided with a large opening which is normally covered by means of a screen 60. Obviously the screen 60 serves to catch and retain any particles which may have failed to settle to the bottom of the tank. Preferably the screen 60 is removable, being normally held in place by means of lugs 61 which enter brackets 62 on the wall 58. 100 105

What I claim is:

1. A washing machine of the class described, comprising in combination a casing open at the ends and having parallel side walls with an opening in one of them, a substantially horizontal endless open-work conveyor for moving the articles to be washed longitudinally through the casing, the said conveyor being located with its lower run at a level above the bottom of the said side opening, a tank at least partly at one side of the casing and below the side opening therein, means for withdrawing liquid from the tank and delivering it against articles being moved by the conveyor, a shield under the lower run of the conveyor for receiving the liquid so delivered and returning it laterally through the side opening into the tank, and a substantially horizontal screen in the casing between the upper and lower runs of the conveyor, the said screen being out of register with the said side opening and serving to receive and retain articles passing through the upper run of the conveyor so as to prevent 110 115 120 125 130

them from being deposited on the lower run thereof.

2. A washing machine as set forth in claim 1, wherein the casing is provided with a side opening adjacent the screen and additional to the first said side opening, and wherein the screen is readily removable through the said additional side opening.

In testimony whereof I have hereunto set
10 my hand this 4th day of May, 1928.
GEORGE WEBB.

15**20****25****30****35****40****45****50****55****60****65**
